UNITED STATES PATENT OFFICE

JOHN O. NEIKIRK, OF CHICAGO, ILLINOIS, ASSIGNOR TO RODGER BALLAST CAR COMPANY, OF CHICAGO, ILLINOIS, A CORPORATION OF MAINE

CAR CONSTRUCTION

Application filed September 5, 1930. Serial No. 479,855.

This invention relates to an improved construction for railroad cars of the type having side walls and open top, and is herein illustrated as applied to a car of the hopper type.

5 More particularly this invention relates to an improved construction of gusset or bracing means for the side walls.

In railroad cars of the type having side walls and open tops which are particularly 10 adapted for the conveyance of loose bulky ladings, such as coal, gravel, sand or other materials similar in kind, it has been found necessary to provide bracing means for the walls of the car whereby to prevent the walls 15 from bulging or otherwise becoming damaged in use. In the past, the bracing strength, has in some instances, been supplied by a transverse bar, or bars, which extends transversely 20 of the car and are connected to the upper edges of the side walls.

Whereas bars of this character supply the necessary bracing strength, objection to their use has been raised for the reason that they interfere with the free movement of various 25 types of implements which are now commonly used in the loading and unloading processes. For instance, in many instances, cars of this character are loaded and unloaded by means 30 of mechanical buckets, shovels or the like which are power controlled from a remote location, and in practice it is found that such loading and unloading implements frequently catch upon, or hit against, bracing bars of the above described type, with the result that the 35 loading or unloading operation is interfered with and furthermore, the bars are bent, broken or otherwise seriously damaged.

In view of this objection, in many instances, 40 bracing plates in the form of gussets have been employed, which are formed as triangular plates of sheet metal and extend transversely across the lower corner of the car between the under frame and the bracing stakes for the side walls.

45 The present invention has to do with an improved bracing gusset of this general character, which is formed of a substantially U construction and comprises a transverse web or sheet, which extends entirely across the 50 car at the extreme lower portion thereof, and

has upstanding portions at the ends thereof for attachment to the side wall stakes. The gusset herein referred to is further provided with means for reinforcing the upper edges thereof throughout its entire length, which reinforcing means is provided on both faces of the gusset at the upper edge thereof in a manner to produce greater strength and resistance to wear than has heretofore been provided.

55 The further object of this invention is to provide a construction of gusset of the type referred to, which is relatively simple in construction, and is capable of being easily and cheaply manufactured, and all the parts of 60 which are highly practical from the commercial standpoint, and admit of ready assemblage.

These and other objects not specifically 65 enumerated, are contemplated for the present invention as will readily appear to one skilled in the art, as the following description proceeds. The particular embodiment of the invention herein given, is merely illustrative 70 of the invention and is not to be considered as limiting in any respect as the scope of the invention should be determined from the appended claims and an understanding of the disclosed embodiment with an appreciation 75 of the advantage which the invention produces therein.

80 The following description may be more readily understood by referring to the accompanying drawings in which:

Figure 1 is a cross sectional view of the 85 body of a hopper car embodying a gusset constructed in accordance with the present invention, and

Figure 2 is an enlarged perspective view of 90 a gusset as shown in Figure 1.

Figure 3 is a plan view of the construction shown in Figure 1.

95 By referring to the drawings, it will be noted that the present invention is illustrated as applied to a hopper or ballast car having the usual under frame 10, side and end walls 11 and 12, respectively. The under frame comprises a center sill 13, and cross beams or struts 15, which are supported by the center sill and serve to support the floor 100

of the car. On the outer ends of the beams 15, side stakes 16 are mounted, which serve as bracing and supporting means for the side walls.

5 For the purpose of strengthening the car body, construction gussets are employed which in accordance with the present invention comprise a transverse plate 18, which extends upwardly from the floor for a portion 10 of the car's height, and is secured at its bottom edge to the beam 15, by means of rivets 19, or other suitable fasteners. The side edges, of the plate 18 are constructed to extend to the side stakes 16, and to be fastened thereto by means of rivets or suitable fasteners not shown.

20 In addition the triangular plates 20 are provided in upstanding relation and are secured to the upper edge of the plate 18, by means of rivets 21, and have their side edges secured to the side stakes 16, in the same manner as the plate 18.

25 It will readily appear from this construction that a bracing gusset of general U formation, is provided, which will serve to strengthen and brace the side walls of the car.

30 For the purpose of reinforcing the upper edges of the gusset described, metallic strips 22 and 23 are placed on opposite faces along the edges thereof and secured by means of rivets or other suitable fasteners 24. The present invention relates particularly to the formation of these strips and to their application as reinforcing and strengthening means for the upper edge of the U shaped gusset. It will be noted that strips 22 and 23 are complementary in formation whereby 35 they jointly provide a U shaped element of the proper configuration to fit the upper edge of the gusset. However, strips 22 and 23 are of different lengths whereby the joint 40 25, at their engaging ends is located to one side of the center line of the car.

45 Another feature of advantage will be realized from an inspection of Figure 2, where it will be noted that the plate 20, on one side of the car, is positioned to overlap the plate 18, on one face of the plate, whereas as the plate 20, at the opposite side of the 50 car, is positioned to overlap the plate 18, on the opposite face thereof. This construction provides the small step 26, produced by the overlapping plates to occur on opposite faces of the gusset at the opposite sides of the car.

55 With this in mind it will be further observed that the strip 22, is provided with a curve or deflection 27, to cause it to properly fit over the step 26, whereupon by the construction of gusset plates above described it is possible to place complementary bracing strips 22 and 23 on both faces of the gusset made up as shown with corresponding portions for the two faces of exactly the same 60 formation, and furthermore, to locate the 65

joints 25, on opposite sides of the center line of the car.

70 As is clearly shown in Figure 2, it will be noted that an extremely simple gusset construction is provided by this invention, and that a high degree of strength is provided by the bracing strips located on the edges of the gusset. Furthermore, by locating the joint 75 25, in the non-registering manner above described, it is possible to manufacture each of the bracing strips in two parts, which is very much simpler and cheaper, without sacrificing strength in the car construction. Whereas, it would be more difficult and expensive to form a single bracing strip of the complete 80 U formation, it is a relatively simple and inexpensive operation to produce the shorter strips having only a single slight curvature.

85 It will also be noted that by locating the upper plates 20, on opposite sides of the plate 18, that both of the shorter strips 22, which are constructed to include the bend or bulge for accommodating the step 26 are of exactly 90 the same construction, and furthermore, strips 23, on both sides are exact duplicates, one of the other. This permits the formation of only two types of strips by a relatively cheap manufacturing process, with a maximum of strength in the final car construction.

95 As is readily known to those skilled in the art, gusset plates of the character herein referred to, are provided in cars at spaced intervals throughout the length thereof, in number according to need and strengthening requirements of the particular car. It will 100 therefore be understood that the present invention contemplates cars having any number of gussets of the above described character as may be required or desirable in practice.

105 I claim:

110 1. In combination with a railroad car having side walls, a gusset extending between and secured to said side walls comprising a lower portion and upstanding side portions secured to opposite sides of said lower portion, and reinforcing means on the upper edge thereof composed of two complementary parts having their jointure to one side of the center of 115 said gusset.

120 2. In combination with a railroad car having side walls, a gusset extending between and secured to said side walls comprising a lower portion and upstanding side portions secured to opposite sides of said lower portion and reinforcing means on the upper edge thereof comprising edge strips on opposite faces of 125 said gusset, having their inner ends in overlapping relation and secured together, and complementary edge strips for said first mentioned strips.

130 3. In combination with a railroad car having side walls, a gusset of general U-formation, and reinforcing means on the upper edge thereof composed of two complementary parts

having their jointure to one side of the center of said gusset.

4. In combination with a railroad car having side walls, a gusset of general U-formation, and reinforcing means on the upper edge thereof comprising edge strips on opposite faces of said gusset having their inner ends in overlapping relation and secured together, and complementary edge strips for said first mentioned strips.

10 Signed at Chicago, Illinois, this 2nd day of September, 1930.

JOHN O. NEIKIRK.
